CIRCULAR KNITTING FULL LENGTH LADY'S
HOSIERY MACHINE

Elwood P. Bellman, Stony Creek Mills, Pa., assignor of twenty-five per cent to James P. Sullivan, Reading, Pa., fifteen per cent to Jeremiah J. Sullivan, Jr., Philadelphia, Pa., and ten per cent to Mark C. McQuillen, Reading Pa.

Application August 22, 1940, Serial No. 353,751

11 Claims. (Cl. 66—134)

This invention relates to a circular knitting full-length ladies' hosiery machine, and more particularly to means adapted thereto, whereby a machine of this character may be made to knit into selected portions of hosiery a reinforcement of a desired design known as a high spliced heel and a cradle sole and to eliminate the excessive waste of yarn and the necessity of trimming an abundance of surplus yarn from the completed hosiery which has heretofore been necessary in ladies' hosiery circular knitting machines, requiring a large number of persons to carry out such work with the possibility of damaging the hosiery and causing a large percentage of seconds or defective hosiery which must be sold at non-profitable prices or discarded at total loss.

Another object of this invention is the provision of a mechanism which may be easily installed on a ladies' hosiery circular knitting machine and includes means for varying the lengths of the courses of the reinforcement to create a selected design and a cutting and clamping means and an operating means therefor, to cut and hold the reinforcing yarn as it is withdrawn from the needles after the knitting of one course of the reinforcement and to release said reinforcing yarn for presentation to the needles for the knitting of the succeeding course with a minimum waste of reinforcing yarn at the ends of the completed courses of the reinforcement.

A further object of this invention is the provision of means for guiding the reinforcing yarn into the path of the cutting and clamping means as said reinforcing yarn is removed from the needles by the reinforcing yarn finger of the knitting machine so as to be cut and held by said cutting and clamping means until such time the reinforcing yarn finger again presents the reinforcing yarn to the needles for the knitting of the succeeding course of the reinforcement.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a fragmentary side elevation illustrating a Scott and Williams circular knitting hosiery machine with the present invention applied thereto.

Figure 22 is a view similar to Figure 21 showing the reinforcement yarn being guided into the path of the cutting and clamping means by the yarn guide with the reinforcement yarn finger in its uppermost position in the act of drawing the yarn from the needles.

Figure 23 is a fragmentary plan view showing the reinforcement yarn engaged by the yarn guide and being brought into position to be engaged by the cutting and clamping means.

Figure 24 is a fragmentary sectional view illustrating the reinforcement yarn approximately leaving or passing off of the yarn guide to be taken up by the needles of the knitting machine.

Figure 25 is a fragmentary sectional view illustrating the reinforcement yarn finger bringing the reinforcement yarn off of the yarn guide into engagement with needles of the knitting machine.

Figure 26 is a view similar to Figure 21 showing the reinforcement yarn finger in position of disengaging the reinforcement yarn from the guide through the cooperation of the needles engaging said yarn and moving in their circular path.

Figure 27 is a fragmentary plan view illustrating a lady's hosiery with a reinforcement therein produced by the present invention on a circular knitting machine of the type above specified.

Figure 28 is a fragmentary plan view of the lady's hosiery indicating diagrammatically the approximate length of the ends of the reinforcing yarn at the ends of the courses.

Figure 29 is a diagrammatical view showing the reinforcement pattern drum and its cam formations.

Figure 30 is a diagrammatical view illustrating the holding and cutting means in one of its inoperative positions.

Figure 31 is a view similar to Figure 30 showing the holding and cutting means in its other inoperative position.

It is to be understood that the present invention is adaptable to various types of well known hosiery knitting machines of the circular type and for the sake of convenience I have elected to show the application of this invention to a

Scott and Williams circular knitting machine known as model K. In the following a brief description of such parts of this machine will be given that will be necessary to bring out a clear conception of the construction and operation of the present invention and its application to the type of machine specified.

The numeral 5 indicates the supporting frame of a model K Scott and Williams circular knitting machine, 6 the bed plate carried by said supporting frame, 7 the needle cylinder and 8 the needles. The usual latch ring for the needles and needle cylinder is indicated by the character 9 and the dial plate is indicated by the character 10. The dial plate head mounting is shown at 11, and is of the usual pivotally mounted type held in operative position with respect to the needles by a latch mechanism 12.

The gap closing mechanism of the knitting machine is indicated generally by the character 12' and includes in its construction a pivotal arm 104 which is swung rearwardly and forwardly with respect to the machine when the gap closing mechanism 12' functions in its usual manner in bringing about the knitting of the hosiery which is minus of reinforcement yarn.

The conventional drive for the dial plate is indicated by the character 13 and includes the usual gear 14 secured on the power shaft 15 journaled on the supporting frame 5. The master control pattern drum of the circular knitting machine is indicated by the character 16 and is shown as journaled on the supporting frame 5 and is slightly modified by providing thereon additional cams for the operation of the present invention on the machine. The additional cam ribs are indicated by the character 17. It is to be understood that the other cam ribs on the master control drum 16 are as usual for the operation of push rods 19, a series of which are clearly illustrated in Figure 2 and which effect the operation of a group of yarn fingers 20 employed for feeding into and taking from the needles yarn at the proper time for knitting of ladies' hosiery. The master control drum is driven as usual from a master timing mechanism or motion changing device 21 forming a standard equipment of this type of machine as well as many other circular knitting machines either for full or half length hosiery and includes the usual control chain 22 having groups of lugs 23 thereon. In adapting the present invention to the machine, additional groups of lugs, indicated by the character 24, are applied to the chain 22. The purpose of the additional lugs, as indicated by the character 24, is to render the present invention operative and inoperative, a more detailed description of which will follow.

It is to be understood that the master timing mechanism or motion changing device is operated or driven as usual from the power shaft 15 and that a train of gears 25 connects the master timing mechanism with the master control pattern drum. The tucking mechanism is indicated in entirety by the character 27 and it is to be understood that the latter is operated as usual by the master timing mechanism or the motion changing device and is only referred to in that a certain timed movement of the rocker 25 thereof brings into operation a part of the present invention, a more detailed description of which will be hereinafter given. The various yarn guides are indicated by the character 28 for the purpose of guiding the different yarns to the yarn fingers 20.

As before stated, the yarn fingers act to feed the different yarns into and out of the needles so that full length ladies' hosiery will be knitted by the machine including a full length leg portion, a reinforced heel, sole and instep portions and a reinforced toe portion, a clear illustration of which is given in Figure 27. It is to be understood that the reinforced heel and toe portions are knitted from a comparatively heavy yarn known as "Lisle" while the foot and leg portions are knitted from real silk or artificial silk yarn.

The machine also includes a reinforcement yarn finger 29 of standard construction for knitting into the ankle and foot portions of the hosiery a reinforcement consisting of a reinforcing yarn knitted in with the usual yarn which goes to make up the hosiery.

In a machine of this character there is no provision made for the stopping of feeding in of the reinforcing yarn and cutting said yarn off after the completion of each course of the reinforcement, consequently resulting in a large surplus of yarn in the foot portion as well as the ankle portion of the hosiery necessitating the employment of persons to cut this surplus yarn from the completed hosiery endangering the hosiery and further adding considerably to the expense of the manufacture of hosiery through the waste of large amounts of reinforcing yarn.

To obviate this surplus accumulation of reinforcing yarn in said portions of the hosiery, the present invention is adapted to the machine and acts to cut off the reinforcing yarn at the end of each course and to hold said yarn from feeding into the needles until such time the machine is ready to knit a succeeding course of the reinforcement. Further, the present invention is so constructed that it will create a selected design in the reinforced portions as indicated or shown in Figure 27 wherein a high spliced heel and a cradle shaped sole with varying lengths to the courses will be produced in the reinforcement to create a selective design thereto, a clear illustration of which is made in Figure 27, and it will be noted that the edges of the reinforcement have certain parts thereof of stepped formation including several courses to each step while other parts of the edges will be substantially straight, all of which is brought about through the use of the present invention on the circular knitting machine of the character specified.

The character 30 indicates a segmental gear forming a part of the usual drive mechanism of the knitting machine of the type specified and is only referred to as it is employed in the actuation of a certain part of the present invention which will be hereinafter more fully described.

The foregoing description briefly sets forth only such parts of the Scott and Williams circular knitting machine that the present invention has direct association with. Therefore, further and more specific description of this machine is not deemed necessary in order to obtain a thorough understanding as to the construction and operation of the present invention when adapted to the machine.

The cutting and holding means forming a part of the present invention is indicated in entirety by the character 31 and is mounted for sliding movement on a supporting bracket 32 carried by the bed plate of the machine. The cutting and holding means enters the machine from a point exteriorly of the needles and operates solely outwardly of the needles.

The reinforcement yarn guide is indicated in

entirety by the character 33 and is mounted on the latch ring outwardly of the needles for pivotal movement and consists primarily of an arm 34 pivotally mounted on a supporting lever 35, as shown at 36. The supporting lever 35 is pivotally mounted on the latch ring, as at 37. The free end of the arm 34 is angularly disposed and has attached thereto a plate 38 provided with a notch 39 which defines spaced guide elements 40 and 41, one disposed slightly laterally of the other and one of a greater length than the other, as clearly shown in Figure 15. The arm 34 is of such a length that when it is pivoted in one direction the plate 38 with the guide elements 40 and 41 will be brought within the annular row of needles 8 adjacent to the reinforcement yarn finger 29 so that during the time the reinforcing yarn finger 29 is moving upwardly to disengage the yarn from the needles, said yarn will move into the slot 39 and extend across one face of the guide 40 and over an opposite face of the guide 41 to position the yarn into the path of the cutting and clamping means 31. When the reinforcing yarn has been severed and released by the cutting and holding means, said yarn being in engagement with the guides as specified will be in position to be again taken up by the needles.

It is to be understood that the arm 34 swings upwardly and downwardly with respect to the needles and when swung upwardly assumes an inoperative position, allowing the reinforcing yarn to get into the main binder 8' which is standard equipment, and leaves the yarn finger 29 clear of the needles which takes place when the machine is knitting other portions of the hosiery than the portion in which the reinforcement is formed.

A connecting link 42 is pivotally connected to the arm 34 of the reinforcement yarn guide 33, as shown at 43, and is in turn pivotally connected to the upper end of a push rod 44 mounted for sliding movement on the machine along with the other push rods 19 and rides the master control drum 16 under spring pressure to be engaged and disengaged by the cam ribs 17; whereby the reinforcement yarn guide 33 will be brought into operative and inoperative positions with respect to the needles. It is to be understood that the master control drum positions the reinforcement yarn guide 33 in an inoperative position during the time that the machine is knitting any portion of the hosiery which does not have the reinforcement therein. The employment of the yarn guide 33 is extremely important to the success of the present invention on the circular knitting machine, otherwise the reinforcement yarn would not be guided into proper position to be cut and held by the cutting and holding means 31 arranged exteriorly of the needle. Also, the reinforcement yarn guide 33 is important in that it guides the reinforcement yarn into the needles when released by said cutting and holding means 31.

The cutting and clamping means 31 consists primarily of a scissor construction including a relatively fixed blade 45 and a pivotally mounted blade 46 to coact with the blade 45 and is pivoted thereto, as shown at 47, and carries on its pivoted end an arcuately curved cam extension 48. A leaf spring 49 is secured to the pivot 47 and bears against the pivoted blade for urging the latter into cutting relation with the relatively fixed blade 45. The spring 49 also coacts with the blade 46 in gripping the yarn when the blades

45 and 46 are in cutting position so that the severed yarn will be held until such time that the blades separate.

The relatively fixed blade 45 is secured on one end of a substantially L-shaped plate 50 which is slidably secured on a block 51 and in which is mounted a spring-pressed plunger 52 acting on the L-shaped plate 50 to urge the scissor construction away from the needles or in a retracted position with relation to said needles. The block 51 is journaled on a vertically arranged shaft 53 and the latter is mounted on a bracket 54 carried by the bed plate 6 of the knitting machine. The bracket 54 also supports a cam guide 55 in which is slidably mounted a spring influenced cam 56, the high and low faces of which are adapted to ride into and out of engagement with the L-shaped plate 50 for advancing the scissor construction towards the needles and to permit the retraction of said scissor construction from the needles during certain operations of the device.

A guide 57 is mounted on the block 51 and receives the cam extension 48 on the pivoted blade 46. When the cam 56 is moved downwardly it advances the blades towards the needles and as said blades travel in the stated direction, the cam extension 48 operating in the guide 57 causes a pivotal movement of the blade 46 towards the blade 45 or in other words, brings about movement of the blade 46 over the blade 45 so as to cut and clamp the reinforcing yarn. When the cam 56 moves upwardly the spring influenced plunger 52 slides the scissor construction away from the needles as before stated and this movement brings about a pivotal movement of the blade 46 away from the blade 45, consequently releasing the reinforcing yarn held thereby. The movement of the blade 46 away from the blade 45 is caused by the cam extension 48 moving in the guide 57.

An adjustable stop 58 is mounted on the bracket 54 for limiting the pivotal movement of the scissor construction or its mounting block 51 in one direction. A spring 59 is connected to the block 51 for urging the latter into engagement with the adjustable stop 58. When the block is in engagement with the stop the scissor construction, consisting of the blades 45 and 46 is positioned in proper alignment to move towards and from the needles.

A curved arm 60 is secured on a gap closing arm 104 carried by the dial head construction and which is movable therewith and when the dial head is elevated to expose the needles the curved arm 60 engages the block 51 and imparts pivotal movement thereto away from the stop 58 bringing about a swinging movement of the scissor construction to completely clear the space in the vicinity of the needles so that a person can conveniently adjust or manipulate the needles without interference from the scissor construction when the dial head is in an elevated position. The scissor construction is now in one of its inoperative positions. However, when the dial head is returned to a latched position, the curved arm 60 disengages from the block 51 and the spring 59 restores the scissor construction in proper position for movement inwardly and outwardly from the needles in the manner heretofore specified.

The cam 56 includes a substantially L-shaped arm 61 which engages with a pivotally mounted lever 62, the pivot of which is indicated by the character 63. The lever 62 is connected by its pivot 63 onto the latch ring 9 of the knitting ma-

chine. One end of the lever 62 is pivotally connected to the upper end of a connecting rod 64 which is adjustable as to length, as indicated at 65. The lower end of the connecting rod 64 is pivoted to one end of a lever 66 pivoted on the rear portion of the knitting machine directly above the master control drum, as shown at 67, and has an upturned end 68 which engages with a lever 69 and also is provided with a notch 70 that will permit pivotal movement of said lever 66 without affecting or moving an arm 71 which substantially parallels the arm 69.

The arms 69 and 71 are of the shape as shown in Figure 16a and are journaled in a bracket 72 mounted on the frame 5 of the machine. Cam levers 73 and 74 have riding contact with the arms 69 and 71, respectively, and are capable of sliding endwise of said arms. The cam levers 73 and 74 are journaled on a shaft 75 and the latter is rotatably and slidably mounted on the bracket 72, also the cam levers 73 and 74 are movable with the shaft 75 in its endwise movement in opposite directions. The cam levers engage with a reinforcement pattern drum 76 fixed on the power shaft 15. The cam levers 73 and 74 contact the reinforcement pattern drum one directly behind the other. The reinforcement pattern drum 76 has a series of cam ribs 78 terminating at their ends in stepped formation so that the cam ribs successively increase in length from one end of the reinforcement pattern drum to the other end. This reinforcement pattern drum effects operation of the cutting and holding means 31 and also the reinforcement yarn finger 20. The arm 71 engages with a lever 79 which parallels the lever 66 and utilizes its pivot 67 as its mounting and engages with a lug 80 secured on the push rod 19 which actuates the reinforcement yarn finger 29.

To adjust the cam levers 73 and 74 with respect to the cam ribs 78 of the reinforcement pattern drum 76, the shaft 75 must have an endwise movement imparted thereto and also in a step by step manner. To accomplish this movement of the shaft 75 to bring about the adjustment of the cam levers 73 and 74 on the reinforcement pattern drum, a ratchet disc 81 is journaled on the bracket 72 outwardly of the said bracket 72 and the journal shaft 82 thereof forms a pivot for a cam lever 83 which is adapted to ride against series of cam elements 84 adjustably mounted on one face of the ratchet disc 81. The other end of the cam lever 83 is connected to the shaft 75, as shown at 85. The cam elements 84 are arranged in a circular path upon the ratchet disc, and are arranged in two groups as shown in Figure 4, that is, the cam elements of one group progress in height from one end of said group to the other end of said group and the cam elements of the other or second group progressively decrease in height.

The ratchet gear 81 is rotated in a step by step movement so that the cam lever 83 rides onto the cam elements 84 which progressively increase in height and then on the cam elements which decrease in height to bring about a sliding movement of the shaft 75 first in one direction and then in an opposite direction to adjust the cam levers 73 and 74 from one of the cam ribs to another of said reinforcement pattern drum 76 until said levers 73 and 74 have completed engagement with all of the cam ribs 78 in one direction of said pattern drum and then adjust said cam levers 73 and 74 over the various cam ribs of the pattern drum 76 in a reverse di-

rection of said pattern drum 76. A spring 74' is connected to the supporting frame 5 and to the shaft 75 for urging the latter in a direction that the cam lever 83 will ride the cam elements 84, and also to draw the shaft 75 in a direction of moving the cam levers 73 and 74 in a reverse direction of the reinforcement pattern drum 76 as the cam lever 83 rides over the group of cam elements 84 which progressively decrease in height.

One of the teeth of the ratchet gear is lower than the remaining teeth and is indicated by the character A and which is located adjacent the lowermost cam element of the group of cam elements which progressively increase in height. The tooth A is for the purpose of setting the ratchet gear 81 for the starting of the knitting of the reinforcement pattern in the fabric of the hosiery.

A friction brake 87 is mounted on the bracket 72 and bears against the ratchet disc 81 with sufficient force to prevent accidental rotation of the ratchet disc.

A rock shaft 88 is journaled on the frame 5 of the machine and has secured to one end an arm 89 which has riding contact with the segmental gear 30 of the drive mechanism of the machine for the purpose of rocking the shaft 88 in opposite directions, it being understood that the segmental gear 30 of the drive mechanism oscillates. An arm 89' is secured to the other end of the rock shaft 88 and has connected thereto a spring 90 which is in turn connected to the bed plate for the purpose of urging the shaft 88 in a direction to maintain the arm 89 in wiping contact with the segmental gear 30.

A dog 91 is pivoted to the arm 89' for coaction with the teeth on the ratchet gear 81 and is spring influenced in the direction of said teeth by a spring 92'.

Sleeves 92 and 93 are journaled on the shaft 75. The sleeve 93 forms a pivot for a bell crank lever 94 which has one end pivotally connected to the sleeve 92 and the other end is pivotally connected to an operating rod 95 which is connected to the rocker 25' of the motion changing device 21 of the knitting machine. A bracket 96 is secured to the sleeve 92 and carries arms 97 and 98 spring influenced towards each other by a spring 98'. The arm 98 is pivoted on the bracket while the arm 97 is fixed thereto and carries a pin 99 which engages with one edge of the arm 98 to swing the latter in one direction or in a direction of holding the dog 91 away from the teeth of the ratchet gear 81. The movement of the rocker 25' causes a movement of the sleeve 92 in one direction which will bring about holding of the dog 91 out of the path of the teeth of the ratchet gear 81 and a movement of the rocker 25' in an opposite direction will so position the arms 97 and 98 that the dog 91 may move into engagement with the teeth of the ratchet gear 81.

The push rod 44 of the reinforcement yarn guide has secured thereto a stop rod 100 which is adapted to underlie the lever 66, as shown in Figure 4, to act as a latch therefor, and also the push rod 44 has adjustably secured thereto a rod 101 provided with an offset 102. The rod 101 is in the path of a pin 99 carried by the dog regulating arm 97, so that when the push rod 44 is on one of the cams 17 of the master pattern drum which positions the yarn guide 33 in an inoperative position, the dog 91 will be held by the arm 98 so that it cannot engage the tooth of the

ratchet disc 81, consequently rendering inoperative the pattern mechanism of the present invention. However, when said push rod rides off of the cam 17, the offset 102 of the rod 101 moves opposite the pin 99 so that the arm 98 will permit the dog 91 to move into position under the influence of the spring 92' to engage with the tooth A and thereby bring about the starting of the stepped movement of the ratchet disc and consequently start the operation of the complete pattern mechanism of the present invention.

During the time the machine is knitting the Lisle heel and toe portions of the hosiery the cutting and holding means 31 is swung on its pivot to assume a position which is entirely clear of the needles. In order to accomplish this, the cam 56 is moved downwardly by the push rod 44 moving on one of the cam ribs 17 of the drum 16 and the stop rod 100 on the push rod 44 engages the lever 66, imparting pivotal movement thereto which moves one end of said lever 66 away from the arm 69 so as to render the cutting and holding means 31 inoperative. During the time the machine is knitting the Lisle heel and toe portions of the hosiery, the cutting and holding means 31 is swung on its pivot to assume a position which is entirely clear of the needles or into an inoperative position. At this time the gap-closing arm 104 of said needles moves rearwardly to bring about knitting of the heel and toe portions and as said arm 104 moves, it swings said cutting and holding means 31 clear of said needles or into inoperative position. At substantially the same time as the above operation takes place, the push rod 34 moves onto one of the cam ribs 17 of the drum 16 and the stop rod 100 engages the lever 66 and imparts pivotal movement thereto which moves one end of said lever 66 away from the arm 69. The pivotal movement of the lever 66 moves the connecting rod 54 upwardly and through the pivot lever 62 pulls the cam 56 downwardly, positioning the high face thereof to one side of the angularly related end of the plate 50 to hold the scissor construction in inoperative position as shown in Figure 31.

The cutting and holding means 31 is also moved into the stated inoperative position by the said means when the knitting machine is knitting the leg portion or that portion which does not have the reinforcement yarn therein.

The cam 56 is held downwardly by the stop bracket 100 on the push rod 44 during all periods of knitting the hosiery by the knitting machine which does not have the reinforcement yarn therein. Consequently, the gap-closing mechanism of the knitting machine must reverse its movement after completing the heel and toe portions to bring about knitting of the fabric which does not have the reinforcement yarn therein and on its return movement it permits the cutting and holding means 31 to swing into a second inoperative position wherein the L-shaped bracket 50 thereof comes in contact with a side face of the cam 56, remaining in this position until the cam 56 is allowed to return to its uppermost position for the operation of the cutting and holding means inwardly and outwardly with respect to the needles.

The foregoing describes the various parts of the present invention and its application to a circular knitting machine of the type specified and also sets forth the parts of said machine to which the various parts of the present invention are connected or associated with.

In the following an operation of the invention in connection with the machine will be set forth.

The operation of the circular knitting machine which has been heretofore briefly set forth, is well known in this art as to the knitting of hosiery fabric which includes the leg and foot portions with the heel and toe portions thereof knitted of a heavier yarn than the leg and foot portions. Therefore, it is not deemed necessary to explain the operation of the machine in detail in this respect.

It is to be understood that the machine is set in operation to knit the leg portion and on the completion thereof one of the lugs of the group of lugs 24 on the chain 22 actuates the motion changing device, so that the rocker 25' thereof is caused to move, which movement actuates the arm 98 to allow the dog 91 to move into a position that will permit it to engage the low tooth A on the ratchet plate 81. At the same time the push rod 44 moves off of the cam ribs 17 on the main pattern drum 16, which positions the offset 102 of the rod 101 opposite the pin 99 to allow the arm 98 to move sufficiently to permit the dog 91 to assume said position relative to the low tooth A. The downward movement of the push rod 44 onto the face of the master pattern drum 16 brings the reinforcement yarn guide 33 into operative position with respect to the needles and the reinforcing yarn finger 29. Said downward movement of the push rod 44, frees the lever 66 for pivotal movement and thereby permits the cam 56 to move upwardly under the influence of the spring connected thereto. When the cam 56 moves upwardly the low face thereof assumes a position to permit the cutting and holding means 31 to swing on its pivot from its second inoperative position to its operative position for movement towards and from the needles. At the time of the push rod 44 moving downwardly, the master control drum 16 permits the reinforcing yarn finger 29 to move into position of presenting the reinforcing yarn to the needles for the knitting of the first series of courses of the reinforcement shown in Figure 27 and designated by the character B. During this period of knitting, the cam levers 73 and 74 are riding the pattern drum 76 between the ends of the first cam ribs 78 thereon when looking at said pattern drum in Figure 4. As each course of the series of courses shown at B of the reinforcement is completed, the cam lever 73 rides on the first cam ribs 78 which brings about movement of the arm 71 which actuates the lever 79 and the latter pushes upwardly on the push rod which actuates the yarn finger 29 into elevated position. This position of the yarn finger 29 takes the yarn from the needles to the yarn guide 33 and the latter guides the reinforcing yarn into a position to be cut and held by said cutting and clamping means 31. Also at this time or just trailing the cam lever 73, the cam lever 74 engages the first cam rib 78 on the pattern drum 76 which actuates the arm 69 and the latter rocks the lever 66 which pushes upwardly on the connecting rod 64 and the latter rocks the lever 62 which pulls the cam 56 downwardly and the latter slides the cutting and holding means 31 towards the needles to cut and grip the reinforcing yarn. This completes one course of the section B of the reinforcement. The cutting and clamping means holds the reinforcing yarn until the machine is ready to knit the next course of the section B of the reinforcement.

The following courses of the section B are accordingly knitted and the reinforcing yarn cut after each of said courses as specified in connection with the knitting of the first courses. At the 5 completion of the first course, the reinforcing yarn is held by the cutting and clamping means 31, the yarn finger 29 again moving downwardly moves the reinforcing yarn over and off of the guide finger 40 which again presents the reinforcing yarn to the needles. This is believed to 10 explain how the device functions in the making of the courses of the section B of the reinforcement and also will explain the knitting of the other courses of the reinforcement minus the 15 forming of the stepped edges of said reinforcement. To form the stepped edges of the reinforcement, the knitting of the courses therein is in accordance with the knitting of the courses of the section B except that the courses which 20 make up the stepped edges are in groups of two or more courses to each step and the courses of each step are of the same length. However, to form the stepped edges of the reinforcement the courses must be increased as to length in the different steps. In order to accomplish this, the 25 cam levers 73 and 74 must be advanced to engage the cam ribs 78 consecutively on the pattern drum 76. To bring about advancing of said cam levers 73 and 74 from one cam rib 78 to the adjacent 30 cam rib 78 another lug of the group of lugs 24 of the chain actuates the rocker 25' of the motion changing device which moves the dog 91 into position to engage the teeth of the ratchet plate 81 for the advance thereof one step. On the advance 35 of the ratchet plate 81 one step, the rocker shaft 88 is actuated by the segmental-shaped gear 30 of the drive mechanism of the knitting machine. The stepped movement of the notched plate 81 slides the shaft 15 a limited distance to bring the cam levers 73 and 74 into engagement with the next cam rib of the pattern drum whereby the knitting of the courses of the second step of the design will be increased in length. The same operation is repeated for the courses 45 of the succeeding steps of the design, except when the design requires the shortening of the courses in the different steps the cam levers 73 and 74 are moved in a reverse direction by the cam lever 83 being actuated by the group of cams 50 84 which decrease in height.

The reinforcement pattern thus formed in the hosiery besides strengthening the latter gives an attractive and neat appearance to the hosiery. Further, the design selected as to the reinforcement 55 in the sole of the hosiery renders that portion of the hosiery form-fitting to the instep portion of the foot.

Further it will be seen that the reinforcing yarn being cut off at the end of each course of the reinforcement will only leave on the interior of the hosiery comparatively short ends to the reinforcement yarn which in no way will detract from the hosiery or render the same uncomfortable to the wearer. However, these short ends of the reinforcing yarn may be conveniently severed or cut off with much less danger of damaging the fabric of the hosiery than is possible when a large surplus amount of yarn is left loose within the hosiery as on a regular type of circular knitting machine.

While I have shown and described the preferred embodiment of my invention, it will be understood that minor changes in construction, combination and arrangement of parts may be made without

departing from the spirit and scope of the invention as claimed.

Having thus described the invention, what I claim is:

1. In a ladies' hosiery circular knitting machine including a knitting mechanism having circularly arranged needles and yarn feed means therefor for the knitting of non-reinforced hosiery fabric, a reinforcing yarn finger operated by said machine for feeding into the needles reinforcing yarn arranged in courses and for removing the reinforced yarn from the needles on the completion of each course, a yarn guide operated by the machine and coacting with the yarn finger in guiding the reinforced yarn into and out of the needles and into a position to be held and cut outwardly of the group of needles, and a combined cutter and holding means operated by the machine to cut the reinforcing yarn withdrawn from the needles on the completion of each course and to hold said reinforcing yarn until such time the yarn finger acts to again present the reinforcing yarn to the needles for the making of the next course.

2. In a ladies' hosiery circular knitting machine including a knitting mechanism having circularly arranged needles and yarn feed means therefor for the knitting of non-reinforced hosiery fabric, a reinforcing yarn finger operated by said machine for feeding into the needles reinforcing yarn arranged in courses and for removing the reinforcing yarn from the needles on the completion of each course, a yarn guide operated by the machine and coacting with the yarn finger in guiding the reinforcing yarn into and out of the needles and into position to be held and cut outwardly of the group of needles and including a plate having a slot defining spaced guide elements one disposed slightly laterally of the other and one of a greater length than the other for the reinforcing yarn to engage with, and a combined cutter and holding means operated by the machine to cut the reinforcing yarn withdrawn from the needles on the completion of each course and to hold said reinforcing yarn until such time the yarn finger acts in cooperation with the yarn guide to again present the reinforced yarn to the needles for the making of the next course.

3. In a ladies' hosiery circular knitting machine including a knitting mechanism having circularly arranged needles and yarn feed means therefor for the knitting of non-reinforced hosiery fabric, a reinforcing yarn finger operated by said machine for feeding into the needles reinforcing yarn arranged in courses and for removing the reinforcing yarn from the needles on the completion of each course, a yarn guide operated by the machine and coacting with the yarn finger in guiding the reinforcing yarn into and out of the needles and into position to be held and cut outwardly of the group of needles and including a plate having a slot defining spaced guide elements one disposed slightly laterally of the other and one of a greater length than the other for the reinforcing yarn to engage with, and a combined cutter and holding means slidably and pivotally mounted on the machine and including a scissor construction to cut the reinforcing yarn withdrawn from the needles on the completion of each course and to hold said reinforcing yarn until such time the yarn finger acts to again present the reinforcing yarn to the needles for the making of the next course,

and means for operating the scissor construction by the machine.

4. In a ladies' hosiery circular knitting machine including a knitting mechanism having circularly arranged needles and yarn feed means therefor for the knitting of hosiery fabric, a reinforcing yarn finger operated by said machine for feeding into the needles reinforcing yarn arranged in courses and for removing the reinforcing yarn from the needles on the completion of each course, a yarn guide operated by the machine and coacting with the yarn finger in guiding the reinforcing yarn into and out of the needles and into position to be held and cut outwardly of the group of needles, a holding and cutting means mounted on and operated by the machine and located outwardly of the group of needles to cut the reinforcing yarn at the completion of each course and to hold said yarn until the yarn finger again acts to present the reinforcing yarn to the needles for the making of next course and includes a scissor construction consisting of pivotally connected blades and a pivotal and slideable mounting for one of the blades on the machine, and a tensioning spring for creating pressure of one blade on the other and to coact with one of the blades in gripping the reinforcing yarn when being cut.

5. In an attachment for circular knitting machines, a holding and cutting mechanism comprising pivotally connected blades adapted for scissor movement, a plate secured to one of the blades, means for slidably supporting said plate, means for sliding the plate in opposite directions, to bodily move said blades in opposite directions, a spring member acting to urge the blades to have binding action on each other when moved in overlapped relation, for cutting yarn and coacting with one of the blades in gripping and holding the yarn, and means for pivoting one blade in relation to the other blade and in opposite directions by the sliding movement of the blades bodily in opposite directions.

6. In an attachment for a circular knitting machine, a holding and cutting mechanism comprising pivotally connected blades adapted for scissor movement, a plate secured to one of the blades, means for slidably supporting said plate, means for sliding the plate in opposite directions, to bodily move said blades in opposite directions, a spring member acting to urge the blades to have binding action on each other when moved in overlapped relation for cutting yarn and coacting with one of the blades in gripping and holding the yarn, a guide on said plate, a curved extension formed on one of the blades and operating in the guide to bring about pivotal movement of the latter-named blade in respect to the other blade during the sliding movement of the blades bodily in opposite directions.

7. In a hosiery circular knitting machine of the character described including a circular knitting mechanism for knitting hosiery fabric having a group of circularly arranged needles and an operating means therefor and a yarn feeding means for said needles, said operating means including a main pattern drum for operating said yarn feeding means, a yarn finger for feeding reinforcing yarn into and out of the needles and for positioning the reinforcing yarn to be held and cut entirely outwardly of the group of needles, a yarn guide on the machine and coacting with the yarn finger for the positioning of the yarn to be cut and for guiding the yarn on its return to the needles by said finger, a holding

and cutting means on the machine to cut the yarn when outwardly of the needles and for holding the yarn until acted on by the finger in restoring the yarn to said needles, means operated by the pattern drum to render said yarn finger and yarn guide operative and inoperative, and means operated by the machine to cause the reinforcing yarn to be knitted into the fabric in a selected design.

8. In a hosiery circular knitting machine of the character described including a circular knitting mechanism for knitting hosiery fabric and having a group of needles for knitting courses and operating means therefor including a main pattern drum, a yarn finger for feeding reinforcing yarn into and out of the needles for knitting said reinforcing yarn into selected areas of the fabric and in courses, a guide for the reinforcing yarn and coacting with the finger in guiding the reinforcing yarn into and out of the needles and into a position to be held and cut at the end of each course, means operated by the pattern drum to render the finger and guide operative and inoperative, means operated by the machine for holding and cutting the reinforcing yarn at the end of each course, a design pattern drum operated by the machine, means operated by said design pattern drum for the control and actuation of the yarn finger to bring about the formation of the courses in a selected design.

9. In a hosiery circular knitting machine of the character described including a circular knitting mechanism for knitting hosiery fabric and having a group of needles for knitting courses and operating means therefor including a main pattern drum, a yarn finger for feeding reinforcing yarn into and out of the needles for knitting said reinforcing yarn into selected areas of the fabric and in courses, a guide for the reinforcing yarn and coacting with the finger in guiding the reinforcing yarn into and out of the needles and into a position to be held and cut at the end of each course, means operated by the pattern drum to render the finger and guide operative and inoperative, means operated by the machine for holding and cutting the reinforcing yarn at the end of each course, a design pattern drum operated by the machine, means operated by said design pattern drum for the control and actuation of the yarn finger to bring about the formation of the courses in a selected design, and within a selected area of the fabric and in groups of courses varying in length with a selected number of courses of the same length in each group.

10. In a hosiery circular knitting machine of the character described including a circular knitting mechanism for knitting hosiery fabric and having a group of needles for knitting courses

and operating means therefor including a main pattern drum, a yarn finger for feeding reinforcing yarn into and out of the needles for knitting said reinforcing yarn into selected areas of the fabric and in courses, a guide for the reinforcing yarn and coacting with the finger in guiding the reinforcing yarn into and out of the needles and into a position to be held and cut at the end of each course, means operated by the pattern drum to render the finger and guide operative and inoperative, means operated by the machine for holding and cutting the reinforcing yarn at the end of each course, a design pattern drum operated by the machine, means operated by said design pattern drum for the control and actuation of the yarn finger to bring about the formation of the courses in a selected area of the fabric and in groups of courses varying in length with a selected number of courses of the same length in each group, said last-named means including cam levers engaging the design pattern drum and movable into selected positions thereon, and means operated by the machine for actuating the cam levers into selected positions.

11. In a hosiery circular knitting machine of the character described including a circular knitting mechanism for knitting hosiery fabric and having a group of needles for knitting courses and operating means therefor including a main pattern drum, a yarn finger for feeding reinforcing yarn into and out of the needles for knitting said reinforcing yarn into selected areas of the fabric and in courses, a guide for the reinforcing yarn and coacting with the finger in guiding the reinforcing yarn into and out of the needles and into a position to be held and cut at the end of each course, means operated by the pattern drum to render the finger and guide operative and inoperative, means operated by the machine for holding and cutting the reinforcing yarn at the end of each course, a design pattern drum operated by the machine, means operated by said design pattern drum for the control and actuation of the yarn finger to bring about the formation of the courses in a selected design and within a selected area of the fabric and in groups of courses varying in length with a selected number of courses of the same length in each group, said last-named means including cam levers engaging the design pattern drum and movable into selected positions thereon, and means operated by the machine for actuating the cam levers into selected positions, said last means including a step by step motion device for the movement of the cam levers into the different positions on the design pattern drum.

ELWOOD P. BELLMAN.
